UNITED STATES PATENT OFFICE.

JAMES W. HAYFORD, OF TIFFIN, OHIO, ASSIGNOR OF ONE-HALF TO GEORGE S. YINGLING, OF SAME PLACE.

DENTAL MOLD.

SPECIFICATION forming part of Letters Patent No. 296,690, dated April 3, 1884.

Application filed November 2, 1883. (No model.)

To all whom it may concern:

Be it known that I, JAMES W. HAYFORD, a citizen of the United States, residing at Tiffin, in the county of Seneca and State of Ohio, 5 have invented certain new and useful Improvements in Dental-Plate Molds, of which the following is a specification, reference being had therein to the accompanying drawings.

This invention relates to certain improvements in dental molds; and it has for its object 10 to provide for the formation of a casting as nearly as possible free from blemishes, and is designed, principally, to be used in making castings of light metal, such as aluminum. 15 This object I attain by the means illustrated in the accompanying drawings, in which—

Figure 1 represents a vertical sectional view of a mold constructed according to my invention, and Fig. 2 a detached view of a portion 20 of the devices for clamping the parts of the mold together.

The letter A indicates a flat metallic plate, provided with an inverted-U-shaped metallic standard or frame, B, through the top of which, 25 at the center, extends a screw, C, which has at its upper end a wheel, D, by means of which it may be turned. The said screw, at its lower end, has swiveled to it a metallic plate, E, which is adapted to set between the lugs F on the top 30 of the upper section, G, of the mold, for the purpose more fully hereinafter set forth.

The letter H indicates a metallic plate adapted to set upon the base before mentioned, and to be secured thereto by means of the clamps 35 I, which clasp the lugs K at opposite sides of the said plate. To the said lugs are secured hollow metallic standards, which are slotted vertically, as shown.

The letter L indicates a short metallic cylinder, which rests upon the plate H, and which is provided with lugs M, which set in the slots in the standards, so as to hold the plate in position. The said cylinder or ring forms a portion of the lower section of the mold. The 45 upper section of the mold consists, in part, of an inverted cylindrical cup, which is also provided with lugs to set in the slots in the standards, so as to cause the two sections to register and hold them relatively in proper 50 position for casting.

The letter N indicates a metallic ring or anulus, to be embedded in the plastic material, which forms a portion of the lower section of the mold, and which is slotted at its upper edge, as indicated by the letter P, for the escape of air, as more fully hereinafter set forth. 55

The letter R indicates a similar larger ring, which is to form part of the upper mold-section, and which is to be embedded in the plastic material therein, the said ring being adapted to fit over the first-mentioned ring when in place, as clearly shown in the drawings. The metallic cup or shell of the upper mold-section is provided with apertures S and T, which lead to ports or gates formed in the plastic material of said upper section, one for the admission of molten metal and the other for the escape of air, as will be explained in the following description of the operation of my invention. 60

The operation of my invention is as follows: An impression is taken from the mouth and a model made in the same manner as for vulcanite work. A rim of wax is formed around the edges of the lower mold-section, and the 65 plastic mixture is poured in until it reaches the edges of said rim. Then, before setting, the model is pressed into the plaster a sufficient distance, and the lower ring is pressed into the plaster around the model about one-third 70 of its width, or far enough to admit of the placing on it of the larger upper ring. The second or larger ring is then placed on the smaller ring, (the wax rim having been removed,) after 75 which the upper section of the mold is filled 80 with plaster, and is pressed down upon the lower section. When set, the sections may be separated and the model removed, and after the formation of the gates and vents the mold is complete. The molten metal is run into the mold 85 by any suitable means, and when the lower section thereof is full the mechanical means to secure the desired pressure are applied to further force the metal into the cavities of the mold and compress and solidly complete the 90 casting of the plate. When the metal of the plate has cooled sufficiently, the flask is opened 95 and the formed plate removed for further treatment in the hands of the dentist. The rings form a tight or partially-tight flask, or, rather, 100

a deep well, which holds the metal, and allows the air and gas to go above the metal and escape through the vents.

Having thus described my invention, what I claim, and desire to secure by Letters Patent, is—

1. The combination, with the base-plate and frame of the device, of the bottom plate and shell forming the lower section of the mold, the lateral lugs on said bottom plate having slotted guide-standards for the sections of the mold and the slotted clamps, whereby the bottom plate is clamped to the base of the mold, substantially as specified.
- 15 2. In combination with the upper and lower sections of the mold and the frame, and bottom plate guide-standards and pressure-screw, the internal rings adapted to fit one within the other and be embedded in the re-

spective matrices of the mold, one of the rings 20 being slotted at its edges for the initial escape of gas or confined air, substantially as specified.

3. The combination, with the frame and its base, of the mold-sections, the bottom plate 25 and slotted guide-standards and clamps, and the pressure-screw having a dovetailed swiveled plate, and the dovetailed projections on the upper section of the mold, with which said plate engages, whereby the upper section may 30 be manipulated accurately with respect to the lower section, substantially as specified.

In testimony whereof I affix my signature in presence of two witnesses.

JAMES W. HAYFORD.
